BASEBALL BASE

Perry C. Goodrick, Fond du Lac, Wis.

Application July 1, 1937, Serial No. 151,354

3 Claims. (Cl. 273—25)

This invention relates to an improvement in a baseball base utilized for marking the several points on the diamond and is especially designed as a playground base for use in playing soft ball.

Bases of this character heretofore employed have been so constructed and have a strap arrangement so combined therewith that the base must always be positioned with one side up and its other side down. The spikes of the players' shoes wear out the top side of the base and it must then be discarded since the base must always be positioned with one side, that is the top side, up and the other side down.

One of the principal objects of the present invention is to provide a base of this character which is readily reversible, that is to say, when one side of the base becomes worn it may be turned over and the other side exposed to take the wear and tear of use. In carrying out the present invention the base is so constructed that both its bottom and top sides are of substantially the same appearance and substantially the same structure so that either side may be used as the top side of the base. The web strap arrangement is so combined with the opposite side edges of the base that it may be employed for anchoring the base to the ground with either side of the base uppermost. In other words, the base structure itself and the strap arrangement are both so constituted and related as to make the base reversible.

Other objects and advantages reside in certain novel features of the construction, arrangement and combination of parts which will be herein-after more fully described and particularly pointed out in the appended claims, reference being had to the accompanying drawing forming a part of this specification and in which:

Figure 1 is a view in top plan showing a base embodying the present invention with the anchoring straps extended;

Figure 2 is a view illustrating the base in bottom plan with the anchoring straps positioned to co-act with the anchoring stake which is illustrated in horizontal cross section;

Figure 3 is a view in transverse vertical cross section taken on line 3—3 of Figure 2;

Figures 4 and 5 are fragmentary detail views in vertical cross section taken on lines 4—4 and 5—5 respectively of Figure 1;

Figure 6 is a view in top plan with parts broken away and illustrating the manner in which the filling and covering of the base are interrelated in the production of the article;

Figure 7 is a plan view illustrating the blank

or sheet which constitutes the covering or enclosure for the filling for the base; and

Figure 8 is a detail perspective view of the anchoring stake.

Referring to the drawing the numeral 10 designates generally the casing or ticking of the base which is constituted of canvas or duck or other suitable textile material adapted to withstand usage of the character to which a base is subjected. This casing 10 encloses a fibrous filling 10 11 of suitable material. Generally the casing is made up of a top 12, bottom 13, and a peripheral connecting wall 14, the top and bottom being quilted together by lines of stitching 15 which extend through the top and bottom and through 15 the intervening fibrous filling. By having the quilting extend entirely through the base both sides are of same general appearance and present the same structure so as to adapt the base for use with either side up.

The casing is made up of a sheet of fabric illustrated in Figure 7 and designated at S. The sheet is folded centrally along the line a and at its ends along lines b and c. Its side edges d are seamed together to provide a bag-like structure into 25 which the filling is stuffed. To provide a hard, compact base the edges e upon the lines of fold b and c are interfolded and then stitched together as indicated at 16. The casing adjacent the line of fold a may be tucked or folded as indicated 30 at 17 and the folded portion stitched together. The quilting extends diagonally or obliquely across the base and in such fashion that the lines of stitching or quilting intersect at right angles. These lines of stitching are designated at 18 and 35 19 in Figures 1 and 2. In addition there is a rectangular quilting or line of stitching adjacent the periphery of the base which gives the edge or periphery of the base a rounded or rib-like appearance.

Web-like anchoring straps designated at 25 and 26 are attached to opposite edges of the base and each is provided at its outer end with a metallic eyelet 27. The inner edge of each anchoring strap is extended in between the side edges of the base 45 as indicated at 28 in Figure 4 and is securely united to the base by the stitching 29 which secures the side edges d together. With this construction the anchoring straps are disposed midway between the upper and lower surfaces of the 50 base and as a consequence may be employed to anchor the base with either side up. When the straps are employed to secure the base in position they are extended under the base and their eyelets overlapped. Through the overlapping and 55

alined eyelets an anchoring stake 30 extends and is driven into the ground.

With a base of this character either side may be employed to take the wear and tear of the 5 spikes of the players' shoes. In other words, the base may be readily reversed. This practically doubles the life of the base.

While I have shown and described one construction in which the invention may be advantageously embodied, it is to be understood that the 10 construction shown has been selected merely for the purpose of illustration or example and that various changes in the size, shape and arrangement of the parts may be made without departing from the spirit of the invention or the scope 15 of the subjoined claims.

The invention claimed is:

1. A baseball base of the character described comprising a flat bag-like casing made up of a 20 sheet of textile material folded upon itself to provide upper and lower sides, a fibrous filling in said receptacle, lines of stitching uniting the end and side edges of the sheet to complete the enclosure of the filling in the receptacle, transversely extending lines of stitches penetrating both sides of the receptacle and its fibrous filling to maintain the base flat and to give both sides of the casing substantially the same quilted structure and appearance whereby the base is 25 reversible, and anchoring straps attached to the opposite edges of the base at a point midway between the upper and lower sides and effective to secure the base in position with either side up.

35 2. A baseball base of the character described comprising a flat bag-like casing made up of a sheet of textile material folded upon itself to

provide upper and lower sides, a fibrous filling in said receptacle, lines of stitching uniting the end and side edges of the sheet to complete the enclosure of the filling in the receptacle, transversely extending lines of stitches penetrating both sides of the receptacle and its fibrous filling to maintain the base flat and to give both sides of the casing substantially the same quilted structure and appearance whereby the base is reversible, and anchoring straps having their inner ends interposed between the opposite portions of the side edges of the receptacle and secured thereto by the lines of stitching which fasten the edges together, said anchoring straps being foldable into substantial parallelism with either side of the base and having eyelets at their adjacent ends adapted to coact with an anchoring stake whereby the base may be releasably secured in position with either side up.

3. A baseball base of the character described comprising a flat bag-like casing of textile material, a filling of fibrous material in said casing, a line of stitching offset inwardly from the periphery of the receptacle and penetrating both sides of the casing and the filling to give a rounded rib-like formation around the entire periphery of the base, stitching inwardly of the rib-like formation and penetrating both sides of the casing and the filling to secure both sides of the casing to the filling and give both sides substantially the same structure and appearance whereby the base is reversible, and anchoring straps attached to the opposite edges of the base at a point midway between the upper and lower sides thereof and effective to releasably secure the base in position with either side up.

PERRY C. GOODRICK.
